CLAIM

The ornamental design for a handle as shown and described herein.

DESCRIPTION

FIG. 1 is a top plan view of a handle, showing my new design;

FIG. 2 is a perspective view thereof;

FIG. 3 is a front elevation view thereof; and,

FIG. 4 is a side elevation view thereof.

The broken lines depict portions of the handle in which the design is embodied that are not considered part of the claimed design.

1 Claim, 3 Drawing Sheets
